DOOR CONSTRUCTION

Application filed July 15, 1930. Serial No. 468,155.

This invention relates to improvements in panel type doors and the like, in which molding is arranged along the lines where the panel joins the side stiles and cross rails.

5 The primary object of the invention is to improve the construction of such doors in such manner that a neater and sturdier door will result, and this object will be better understood from a detail description of the 10 improved door.

With the foregoing object outlined and with other objects in view which will appear as the description proceeds, the invention consists in the novel features hereinafter described in detail, illustrated in the accompanying drawings, and more particularly pointed out in the appended claims.

In the drawings,

Fig. 1 is an elevation of one corner portion 20 of a door made in accordance with the invention.

Fig. 2 is a sectional view of the same on the line 2—2 of Fig. 1.

Fig. 3 is an enlarged sectional view of a 25 detail to illustrate the manner of assembling the door.

Referring to the drawings, 4 designates the central panel, 4a the top rail, 4b one of the side stiles, 5 the mitred insert frame, and 30 6 the insert molding of the improved door. It will of course be understood that the panel 4 is of rectangular form, surrounded by the rectangular frame 5, and that the latter is bordered by the rectangular frame formed by 35 the side stiles and cross rails.

The panel 4 may be solid or veneered, and the rails and stiles may be solid or veneered. The drawings illustrate the panel and one 40 of the rails as veneered. The frame 5 also may be either solid or made from veneered material, but it is illustrated as solid.

Doors of this type in the past have been made in various ways. The molding 6 in the most common method has been nailed at the 45 points marked A, to the insert frame 5, and as the molding is thin, it is necessary to place the nails rather close together, and the molding at the edges B is apt to move away from the insert frame, and leave a slight space 50 between the molding and said frame. Such

a construction is not only objectionable for this reason, but the numerous nail holes at the points A, require puttying before the door is either painted or varnished. In the varnished door, the nail holes always show as a 55 disfigurement.

In accordance with the present invention, it will be noticed that the insert frame is under-cut along the lines C, at opposite sides of the frame to provide substantially V-shaped projecting tongues C'. The molding 6 is under-cut on one edge to fit the under-cut on the frame 5, in such a way as to form lips 7 which overlap the tongues C. The lip is a rather important feature, in that it covers any unevenness in the sharp corners of the tongues. The molding, in practice, is nailed from the outer edge, as shown at 8, and these nails of course extend into the insert frame. Owing to the improved construction, the nails are spaced widely apart, as they are only used to hold the molding firmly in position before the panel 4 is assembled in the stiles and rails. It is not necessary to have as many nails as used heretofore, 65 and the nails are all concealed, as their heads are covered by the stile and rail members.

It will be observed that the opposite faces of the frame 5 are so cut as to leave spaces 9 between the frame and the molding. Such 70 spaces allow slight variations in the shape of the molding, and permit perfect joints of the molding with the insert frame, which of course, is very desirable.

The stiles and rails are under-cut along the 75 lines 10 to receive the step-shaped outer edges of the molding, so that the molding enters the stiles and rails for a short distance.

Tongues 11 project from the edges of the insert frame, and they enter corresponding 80 grooves 11a in the stiles and cross rails, whereby when the latter are assembled, the molding and frame 5 are tightly interlocked 85 with the rails and stiles, and solid portions of the rails and stiles act to hold the molding in interlocked relation with the frame 5. In other words, this construction securely anchors the panel in the door frame.

The process of manufacturing the door is to make the insert frame 5 with mitred cor- 90

ners, as shown at 5a, and to fit the edges of the panel into grooves 5b of the frame, as the frame members are assembled. After the frame 5 has been made in this manner and connected to the panel, the panel is run through a double panel raiser which makes the under-cuts C, both under-cuts being made in one operation on the two parallel sides 12. Subsequent to the time that the insert frame 5 is machined in this manner, the moldings 6 which have been run in the usual manner on a molder, are mitred and attached to the insert frame by nailing them from their outer edges with the nails 8 spaced about a foot apart. After the moldings have been attached in this way, the insert frame is complete and is assembled in the stiles and rails as a complete panel; the stiles and rails having previously been prepared with the grooves 10 and 11a to receive the tongues 11, and the whole is placed in an ordinary door clamp in the usual manner.

While a door of this character may be made in various ways, it has been found that the above construction is the most practical way to make the same and avoid the disfigurement of nail holes showing in the surface of the moldings; besides, the molding is held much more securely when nailed separate from the face. This also makes a considerable saving in labor, as in the ordinary method of nailing the molding on to the insert frame, it requires from 50 to 60 small brads to hold the molding in position. With the described construction, this number may be reduced about one-half. Furthermore, as the nails are very small and heretofore had to be set in the molding, the time required is considerable, whereas if the molding is nailed from the back, as described herein, it is not necessary to set the nails, and it is much easier to apply them.

From the foregoing it is believed that the construction and advantages of a door in accordance with the invention may be readily understood by those skilled in the art, and it is apparent that changes may be made in the details disclosed, without departing from the spirit of the invention, as expressed in the claims.

What is claimed and desired to be secured by Letters Patent is:

1. A door including an insert frame having its opposite faces under-cut, molding strips having complementary under-cut surfaces engaging the under-cut surfaces of the frame, and stile and cross rail members having grooves into which the outer edges of the frame and molding strips extend.
2. A door including an insert frame having its opposite faces under-cut, molding strips having complementary under-cut surfaces engaging the under-cut surfaces of the frame, and stile and cross rail members having grooves into which the outer edges of the

frame and molding strips extend, each molding strip having a lip overlapping a face of the frame.

3. A door including an insert frame having its opposite faces under-cut, molding strips having complementary under-cut surfaces engaging the under-cut surfaces of the frame, and stile and cross rail members having grooves into which the outer edges of the frame and molding strips extend, the inner surfaces of the under-cut portions of the molding strips being spaced from the frame.

4. A door including an insert frame having its opposite faces under-cut, molding strips having complementary under-cut surfaces engaging the under-cut surfaces of the frame, and stile and cross rail members having grooves into which the outer edges of the frame and molding strips extend, the under-cut portions of the frame providing projecting tongues, and the molding strips having grooves to receive said tongues.

5. A door including an insert frame having its opposite faces under-cut, molding strips having complementary under-cut surfaces engaging the under-cut surfaces of the frame, stile and cross rail members having grooves into which the outer edges of the frame and molding strips extend, and nails extending through the outer edges of the molding strips into the insert frame.

6. A door or the like comprising an insert frame member under-cut at one side thereof to provide a groove extending toward the central portion of the frame, and a tongue projecting outwardly away from the central portion of the frame, a molding having its inner edge under-cut to provide a groove into which the tongue extends, and means for securing the molding to said frame member.

7. A door or the like comprising an insert frame member under-cut at one side thereof to provide a groove extending toward the central portion of the frame, and a tongue projecting outwardly away from the central portion of the frame, a molding having its inner edge under-cut to provide a groove into which the tongue extends, and means for securing the molding to said frame member, the inner surface of the molding adjacent to the groove, being spaced from the outer surface of the frame member.

8. A door or the like comprising an insert frame member under-cut at one side thereof to provide a groove extending toward the central portion of the frame, and a tongue projecting outwardly away from the central portion of the frame, a molding having its inner edge under-cut to provide a groove into which the tongue extends, means for securing the molding to said frame member, and a lip on the molding projecting toward the central portion of the frame and overlapping a face of the frame member adjacent to the under-cut portion of the latter.

9. A door of the character described, comprising an insert frame member, molding strips on opposite sides thereof and having their inner edges extending into and interlocked with portions of the frame member, the outer edges of the frame member and the molding strips forming a stepped shaped tongue, and an outer frame member having a stepped shaped groove to receive said tongue.

10. A door of the character described, comprising an insert frame member, molding strips on opposite sides thereof and having their inner edges extending into and interlocked with portions of the frame member, the outer edges of the frame member and the molding strips forming a stepped shaped tongue, an outer frame member having a stepped shaped groove to receive said tongue, and nails extending through the tongue portions of the molding into the insert frame member and having their outer ends covered by said outer frames.

11. A door comprising a panel, an insert frame having its inner edges grooved, the edges of the panel extending into said groove, the opposite sides of the frame being undercut to provide substantially V-shaped tongues projecting toward the outer edges of the frame, molding strips arranged on opposite sides of the frame and having substantially V-shaped grooves into which the tongues extend, each molding strip having a lip projecting toward the panel and overlapping a side face of the insert frame, the outer edges of the molding strips and frames forming tongues, and an outer frame having grooves into which the last mentioned tongues project.

12. A door comprising a panel, an insert frame having its inner edges grooved, the edges of the panel extending into said groove, the opposite sides of the frame being undercut to provide substantially V-shaped tongues projecting toward the outer edges of the frame, molding strips arranged on opposite sides of the frame and having substantially V-shaped grooves into which the tongues extend, each molding strip having a lip projecting toward the panel and overlapping a side face of the insert frame, the outer edges of the molding strips and frames forming tongues, an outer frame having grooves into which the last mentioned tongues project, and nails passing from the outer edges of the molding strips into the frame.

13. A door comprising a panel, an insert frame having its inner edges grooved, the edges of the panel extending into said groove, the opposite sides of the frame being undercut to provide substantially V-shaped tongues projecting toward the outer edges of the frame, molding strips arranged on opposite sides of the frame and having substantially V-shaped grooves into which the tongues ex-

tend, each molding strip having a lip projecting toward the panel and overlapping a side face of the insert frame, the outer edges of the molding strips and frames forming tongues, and an outer frame having grooves into which the last mentioned tongues project, the inner surfaces of the molding strips adjacent to the grooves of the molding, being spaced from the side surfaces of the insert frame.

In testimony whereof I affix my signature.
EMIL C. LOETSCHER.
